(57) **CLAIM**

The ornamental design for a soldering iron main body, as
shown and described.

DESCRIPTION

FIG. 1 is a front view of a soldering iron main body showing
my new design.

FIG. 2 is a rear view of the soldering iron main body shown
in FIG. 1.

FIG. 3 is a right side view of the soldering iron main body
shown in FIG. 1.

FIG. 4 is a left side view of the soldering iron main body
shown in FIG. 1.

FIG. 5 is a top view of the soldering iron main body shown
in FIG. 1.

FIG. 6 is a bottom view of the soldering iron main body
shown in FIG. 1; and,

FIG. 7 is a top, right side perspective view of the soldering
iron main body shown in FIG. 1.
